UNITED STATES PATENT OFFICE.

JAMES G. ARNOLD, OF TORONTO, ONTARIO, CANADA.

ILLUMINATED SIGN.

1,341,251.

Specification of Letters Patent.

Patented May 25, 1920.

Application filed June 24, 1919. Serial No. 306,292.

To all whom it may concern:

Be it known that I, JAMES G. ARNOLD, an American citizen, residing at Toronto, in the Province of Ontario, Dominion of Canada, have invented a new and useful Illuminated Sign, of which the following is a specification.

This invention has reference to illuminated signs, and its object is to provide a glass sign character of ornamental appearance particularly visible, both by direct light reflected from its visible surface and by light transmitted through the character, whereby the character is strikingly observable either by daylight or at night.

In accordance with the invention, the sign character is formed of glass and may be pressed or molded from a sheet of glass of more or less translucent nature, the preferable kind of glass being known as opal glass, although other kinds of glass may be employed. It has heretofore been proposed to produce sign characters from sheets of glass molded or pressed into shape with the sign characters either flat or in relief, or sometimes depressed. These different forms of sign characters are objectionable in certain respects in that they either do not illuminate well in both artificial light and daylight, or, in the case of characters in relief, the effect is more or less interfered with, especially when the character is viewed at a considerable angle from one side.

The invention provides a sign character in which the outlines of the strokes are raised or are in relief with respect to the body of the sign character and by appropriately coloring the relief outlines a pleasing effect is produced and the visibility of the character is greatly increased.

The invention will be best understood from a consideration of the following detailed description taken in connection with the accompanying drawing forming part of this specification, with the understanding, however, that the invention is not confined to any strict conformity with the showing of the drawing, but may be changed and modified so long as such changes and modifications mark no material departure from the salient features of the invention as expressed in the appended claims.

In the drawing:

Figure 1 is a face view of a sign embodying the invention.

Fig. 2 is a section through the sign char-

acter on the line 2—2 of Fig. 1, but drawn on a larger scale.

Fig. 3 is a rear face view of the glass portion of one of the sign characters.

Fig. 4 is a section of the glass portion of the sign character on the line 4—4 of Fig. 1.

Referring to the drawing there is shown a frame 1 which may be considered as of suitable size and inclosing an appropriate number of separate sign characters 2. Such sign characters are usually carried by stencil plates 3 each individual to a sign character, and where the characters demand it, the stencil plates have filler portions 4, the plates and filler portions being of opaque material, usually sheet metal. Within the frame 1 back of the sign characters are illuminating devices 5 usually in the form of incandescent electric lamps.

The invention has to do particularly with the sign characters 2 themselves and so no further description need be given of the other parts of the sign, since such other parts are not new in illuminated signs.

Each sign character 2 is formed of a sheet 6 of glass preferably, though not necessarily, of the kind known as opal or milk glass which is more or less translucent, thereby breaking up any markedly distinct view of the illuminating elements represented by the electric lamps 5, and producing a softness of illumination pleasing to the eye of the observer. Opal or milk glass has a further advantage of being pleasingly visible by daylight.

Projecting from the outer face of the glass sheet 6 are parallel or substantially parallel hollow ribs 7 outlining intervening portions 8 of the glass sheet and together forming the character strokes, that is, each character stroke is formed of a plain portion 8 with relief hollow ribs 7 on opposite sides thereof. The character strokes are therefore in relief, but the relief part is confined to the marginal portions of the strokes. This permits the application of coloring matter 9 to the inner faces of the hollow ribs, such coloring matter being of more or less transparent character. The result is that by daylight and without any back illumination the sign characters appear white, or practically so, with the margins of the strokes outlined and made particularly distinct by the outstanding or relief ribs. At night with the illuminating units back of the sign characters glowing, these characters appear

in the main white but are outlined with color produced by the coloring matter 9 on the rear faces of the ribs. The characters are made to stand out with greater prominence than usual by the outlining with a suitable color so that the character is not only rendered more distinct than if of one appearance throughout, but it is also particularly pleasing to the eye. Moreover, sign characters are usually so positioned that the observer is customarily out of direct line therewith, say to one side of or below the side. Under such circumstances the outstanding marginal ribs outlining the sign characters render them more distinct, with the relief margins on opposite sides of each stroke standing out distinctly and in no wise interfered with by the central or main body portions of the character strokes. The distinctiveness of visibility is true whether the sign character be viewed by daylight, and hence be seen by light reflected from the outer face of the sign, or the sign character be viewed by artificial light with the illuminating units back of the observed face of the sign character.

The invention is not restricted to the use of opal or milk glass, since other glass, particularly of translucent character, may be used, and the invention is not restricted to the use of any particular color of the outlining ribs of the character strokes.

The invention is not limited to the plain portion of the character strokes between the ribs being flat, for such plain portion may be more or less concave. When the body of the character stroke is in the same plane as the glass plate of which the character is formed, there is better illumination at night than when such portion of the character stroke is either raised or depressed, but such flat form lacks the effectiveness from an angle that is possessed by the raised stroke form. The invention, however, combines the advantages of both the flat plate form and the raised character stroke form by combining with the flat plate form the raised margins, which latter are particularly effective when interiorly colored, thereby contrastingly outlining the character strokes with no parts of the character strokes hidden as would occur if the margins were colored and the bodies of the strokes were convex. It is to be understood that the showing of the coloring matter 9 appearing in Figs. 2 and 4 is greatly exaggerated in thickness because of the practical impossibility of showing a proper thickness in proportion to the other parts of the drawing.

60 By forming the edge or outlining portions of the sign character strokes of ribs projecting half an inch more or less from the plane of the sign character, such character will be rendered more visible at any angle than other sign characters. By providing

the outlining colored edges in relief the character strokes are rendered visible to a greater distance than other sign characters. Commercially the sign character, by including its own outline, may be more cheaply constructed, and provides a sign character with a permanently colored outline visible at night and an all-white effect by daylight. The construction of the sign character also contributes to ample illumination with less candle power of the illuminants.

It is to be understood that the invention is adaptable to either single face or double face illuminated signs.

What is claimed is:—

1. A sign character for illuminated signs having the character strokes formed of light transmitting material, with each stroke marginally outlined by separated hollow relief ribs of the same material.

2. A sign character for illuminated signs having the character strokes formed of light transmitting material and outlined with marginal ribs of the same material, said ribs being hollow and coated interiorly with coloring matter transmissible of light.

3. A sign character for illuminated signs having the character strokes formed of glass outlined by integral hollow glass margins in relief and characteristically different in illuminating effect from the portions of the strokes between the margins.

4. A sign character for illuminated signs, comprising a plane sheet of glass with relief character strokes outlined by relief spaced ribs characteristically different in appearance to an observer from that of the sheet of glass and the spaces between the ribs.

5. A sign character for illuminated signs having its strokes of light diffusive glass with the margins of the strokes spaced apart and in relief on the observed faces of the strokes, the inner faces of the marginal portions of the strokes being colored with a light transmitting color.

6. A sign character for illuminated signs having substantially flat character strokes of translucent glass with outlining stroke margins in hollow relief formed in one piece with the character strokes and colored on the inner or hollow faces, whereby the sign character with its outlining margins is of one color throughout by daylight, and by artificial light passing through the sign character, the margins of the latter are colored in accordance with the color given to said margins on their inner faces.

In testimony, that I claim the foregoing as my own, I have hereto affixed my signature.

JAMES G. ARNOLD.
